UNITED STATES PATENT OFFICE.

FREDERICK C. BENDER, OF MINEOLA, NEW YORK.

TOY.

Application filed January 2, 1926. Serial No. 78,864.

My invention relates to toy aeroplanes and more particularly to such devices used as a watercraft having a hollow airtight body adapted to receive a quantity of harmless 5 gaseous forming chemical which when mixed with water will cause the gas to expand and expel the water therefrom whereby the machine is propelled.

An important object of my invention is to 10 provide a toy of this character which may be used submerged in a container of water or which may glide along the surface thereof.

Another object is to provide a convenient 15 method of replenishing the supply of gas forming chemical.

Other objects and advantages including an adjustable arrangement of the wings, rudder, stabilizers, etc., whereby a realistic 20 motion of the machine is accomplished and the construction of a simple, practical and inexpensive toy of this character will become apparent from the following detailed description when viewed together with the 25 accompanying drawing forming part hereof, in which

Figure 1 is a side elevational view of my invention shown submerged.

Figure 2 is a cross sectional view taken on 30 a line 2—2 of Figure 1.

Figure 3 is a longitudinal sectional view thereof.

Figure 4 is a detailed view of the chemical cartridge, and

Figure 5 is a sectional view thereof taken 35 on a line 5—5 of Figure 4.

Referring now to the drawings wherein for the purpose of illustration I have disclosed a preferred form of my invention, I 40 provide a hollow body 5, circular in cross section and tapering at each end, the rear end terminating into a blunt point and the forward end cut off sharply thereby forming a circular opening giving access to the interior of the body. The mouth of said opening is provided with a sleeve 6 which is tapered on its outer side to conform to and fit tightly within said mouth, said sleeve also having a central threaded opening adapted 45 to receive the threaded portion of a hollow plug 7 which comprises the means of closing said opening. The plug is provided with an annular shoulder 8 which abuts the edge of said opening and which may have its periphery knurled so as to provide a gripping 50 means for engaging or disengaging the

parts. The outer end of said plug tapers to a blunt point and has mounted thereon a propeller 9 adapted to freely rotate.

A cylindrical cartridge 10 is fitted within 60 the inner end of said plug, the outer end of said cartridge is closed and has an annular shoulder 11 providing gripping means to withdraw the same. The walls of said cartridge are provided with perforations 12 65 and the inner walls of said plug are also provided with perforations preferably in the form of slots 12. The cartridge is adapted to be filled with a suitable quantity of bromo seltzer or other suitable effervescent powder 70 which expands and forms a harmless gas upon contact with water.

Near the rear end of the body and at the bottom thereof I provide an exhaust pipe 14 which communicates with the interior of the 75 body. The exhaust pipe is slightly arcuate in shape and extends in a rearward direction, resembling somewhat the skids commonly provided on the rear of airplanes and said exhaust pipe is adapted to serve one of 80 the functions of such skids, that is to support the machine when motionless in a substantially horizontal plane. A wheel 15 is mounted on the forward end of the body and a keel 16 is also provided on the underneath side of the body to balance the device. 85

The propulsion of the machine is caused by filling the body nearly full of water then inserting the plug carrying the cartridge which is filled with a suitable effervescent 90 powder as above explained. The machine is then placed in an aquarium, tub or other large container of water, and sinks to the bottom. As soon as the water comes in contact with the powder a gas is created which 95 tends to force the water out of the body through the exhaust pipe thereby urging the machine forward. As the water is expelled and more gas is formed the machine becomes lighter and moves upwardly toward 100 the surface as well as forwardly.

The usual airplane wings 17 are provided at each side of the body near the forward end and likewise a rudder 18 and rear stabilizing planes 19 are provided at the tail, 105 these attachments being secured by pins which fit tightly in openings formed in the body so that these parts may be inclined at any desired angle and maintained in such position. Thus the steering and elevational controls may be set so that the machine will 110 perform numerous aerial stunts.

While I have shown a submerged type of machine as a preferred form of my invention, it is to be understood that the same can also be readily adapted as a surface craft by attaching a suitable pontoon or float and it may also be possible to modify certain details of construction without departing from the spirit of the invention or the scope of the appended claims, and I accordingly claim 10 as my own all such modifications to which I am entitled.

I claim:

15 1. A toy comprising a hollow body adapted to receive a quantity of water, an opening at one end thereof, a threaded hollow plug adapted to fit in said opening, a cartridge slidably fitted within the inner end of said plug, a gas forming powder within said cartridge, openings in the walls of said cartridge, and said plug, and an exhaust port at 20 the opposite end of said body for expelling said water and said gas.

25 2. A toy comprising a hollow body adapted to receive a quantity of water, an opening at one end thereof, a threaded hollow plug adapted to fit in said opening, a cartridge slidably fitted within the inner end of said plug, a gas forming powder within said cartridge, openings in the walls of said cartridge and said plug, an exhaust port at 30 the opposite end of said body for expelling said water and said gas, and directional and elevational controlling means carried on the outside of said body.

35 3. A toy comprising a hollow body, an opening formed in one end thereof, a removable plug adapted to seal said opening and extending outwardly from the body in continuation of the contour thereof, an exhaust port at the other end of said body and means

carried within said plug for propelling said body.

4. A toy comprising a hollow body, an opening formed in one end thereof, a removable plug adapted to seal said opening and extending outwardly from the body in continuation of the contour thereof, an exhaust port at the other end of said body and means carried within said plug for creating a gas in said body for discharging through 45 said exhaust port.

5. A toy comprising a hollow body, an opening at one end thereof, a removable threaded plug adapted to seal said opening and extending outwardly from the body in 55 continuation thereof, a cartridge carried by said plug, means carried by said cartridge for forming a gas within said body and an exhaust port at the other end of said body for expelling said gas.

6. A toy comprising a boat shaped body arranged to hold a supply of liquid, a plug threaded fitted in the forward end thereof and extending outwardly therefrom and forming a bow end for the boat in continuous contour therewith, an exhaust port in the opposite end thereof and a liquid expelling cartridge telescopically carried in said plug.

7. A toy comprising a boat shaped body arranged to hold a supply of liquid, a plug threaded fitted in the forward end thereof and extending outwardly therefrom and forming a bow end for the boat in continuous contour therewith, an exhaust port in the opposite end thereof and a liquid expelling cartridge carried by said plug and movable longitudinally in said body.

In testimony whereof I affix my signature.

FREDERICK C. BENDER.
